(57) **CLAIM**

The ornamental design for the container with pump actuator, as shown and described.

DESCRIPTION

FIG. 1 is a top, right and front perspective view showing our new design for a container with a pump actuator illustrated in a locked position;

FIG. 2 is a top, left and rear perspective view thereof;

FIG. 3 is a top and front perspective view thereof;

FIG. 4 is a bottom and rear perspective view thereof;

FIG. 5 is a front elevation view thereof;

FIG. 6 is a rear elevation view thereof;

FIG. 7 is a left side elevation view thereof;

FIG. 8 is a front and left elevation view thereof;

FIG. 9 is a right side view thereof;

FIG. 10 is a top plan view thereof;

FIG. 11 is a bottom plan view thereof;

FIG. 12 is a top, right and front perspective view shown illustrated in an unlocked and unpressed position;

FIG. 13 is a top, left and rear perspective view thereof;

FIG. 14 is a top, front and left perspective view thereof;

FIG. 15 is a bottom, left and front perspective view thereof;

FIG. 16 is a front elevation view thereof;

FIG. 17 is a rear elevation view thereof;

FIG. 18 is a left side elevation view thereof;

FIG. 19 is a front and left elevation view thereof;

FIG. 20 is a right side view thereof;

FIG. 21 is a top plan view thereof; and

FIG. 22 is a bottom plan view thereof.

FIG. 23 is a top, right and front perspective view shown in an unlocked and depressed position;

FIG. 24 is a top, left and rear perspective view thereof;

FIG. 25 is a top, front and left perspective view thereof;

FIG. 26 is a bottom, left and front perspective view thereof;

FIG. 27 is a front elevation view thereof;

FIG. 28 is a rear elevation view thereof;

FIG. 29 is a left side elevation view thereof;

FIG. 30 is an a front and left elevation view thereof;

FIG. 31 is a right side view thereof;

FIG. 32 is a top plan view thereof; and,

FIG. 33 is a bottom plan view thereof.

The dashed line circle shown in FIGS. 4, 11, 15, 22, 26, and

33 depicts a portion of the container with pump actuator that

forms no part of the claimed design.
